ROLL GRINDING MACHINE

Albert G. Belden and Herbert J. Griffing, Worcester, Mass., assignors to Norton Company, Worcester, Mass., a corporation of Massachusetts

Application January 14, 1936, Serial No. 59,008

7 Claims.

(Cl. 51—95)

This invention relates to grinding machines, and more particularly to a roll grinding machine for grinding a convex or concave crown on a roll.

One of the objects of this invention is to provide a simple, thoroughly practical roll grinding machine for grinding a predetermined crown on the periphery of a roll. Another object is to provide a roll crowning apparatus of a simplified form in which either a concave or a convex roll 10 may be ground. A further object of this invention is to provide a roll grinding machine with a crowning device in which the extent of crown produced may be readily adjusted. Other objects will be in part obvious or in part pointed out 15 hereinafter.

The invention accordingly consists in the features of construction, combinations of elements, and arrangements of parts, as will be exemplified in the structure to be hereinafter described, and 20 the scope of the application of which will be indicated in the following claims.

In the accompanying drawings in which is shown one of the various possible embodiments of the mechanical features of this invention,

25 Fig. 1 is a front elevation of a roll grinding machine embodying this invention;

Fig. 2 is a fragmentary plan view of the roll grinding machine shown in Fig. 1;

30 Fig. 3 is a fragmentary front elevation, on an enlarged scale, of the table traverse control mechanism;

Fig. 4 is a sectional view through the table traverse mechanism taken approximately on the line 4—4 of Fig. 3; and

35 Fig. 5 is a fragmentary side elevation of the grinding wheel supporting slide and the feeding mechanism, having parts broken away to more clearly show the construction.

40 As illustrated in the drawings, a roll grinding machine has been illustrated in the drawings comprising a base 10 having a pair of swivel bases 11 and 12 which are pivotally connected to the base 10 by the pivot pins 13 and 14 which are preferably located adjacent the inner ends 45 of the bases 11 and 12 respectively.

An adjusting mechanism is provided adjacent to the outer end of each of the swivel bases 11 and 12 so that the bases may be adjusted into alignment with each other or at an angle to each other to produce either a convex or a concave crown on the work piece being ground. The swivel base 11 is provided with outwardly extending brackets 15 and 16 which are provided with opposed adjusting screws 17 and 18 which are screw threaded into the brackets 15 and 16 re-

spectively and are arranged to engage the front and rear surfaces of the base 10. The end of the swivel base 11 is provided with an index finger 19 which is arranged opposite to a graduated scale 20 on the base 10. It will be readily apparent from the foregoing disclosure that by adjusting the screws 17 and 18, the swivel base 11 may be adjusted relative to the base 10. The adjustment may be made in accordance with the graduated scale 20 so that the swivel base 11 may be 10 adjusted so that its ways are parallel to the base 10 or at an angle thereto, as illustrated in Fig. 2, for grinding a convex crown on the roll being ground.

Similarly, the outer end of the swivel base 12 15 is provided with transversely extending brackets 21 and 22 which carry adjusting screws 23 and 24 respectively. The adjusting screws 23 and 24 are screw threaded into the brackets 21 and 22 and are arranged to engage opposite surfaces of 20 the base 10 to permit adjustment of the swivel base 12 relative thereto. The swivel base 12 is provided with an index finger 25 which is arranged to cooperate with a graduated scale 26 on the base 10, so that the swivel base 12 may 25 be adjusted into the desired angular position relative to the base 10. The swivel base 11 is provided with a V-way 30 and a flat way 31 which serve to support a longitudinally movable table 32 thereon. The swivel base 12 is provided with a V-way 35 and a flat way 36 which serve to slidably support a longitudinally movable table 37. A work supporting table 40 is pivotally connected to the tables 32 and 37 by means of pivot pins 41 and 42, so that the table 40 is moved longitudinally by movement of the tables 32 and 37.

30 The work supporting table 40 is provided with a rotatable work support for a roll 45 to be ground. The rotatable work support may comprise a headstock 46 and a footstock 47 which are provided with work supporting centers 48 and 49 which serve to support and rotate the roll 45.

40 A rotatable grinding wheel 50 is supported on a wheel spindle 51 which is in turn rotatably 45 supported on a transversely movable wheel slide 52. The grinding wheel slide 52 is provided with ways 53 which mate with correspondingly shaped ways (not shown) on the base 10. The grinding wheel spindle 51 is preferably rotated by means 50 of an electric motor 55 mounted on the upper surface of the wheel slide 52. The motor is provided with a driving pulley 56 which is connected by driving belt or belts 57 with a pulley 58 mounted on the end of the wheel spindle 51. 55

The grinding wheel slide 52 is arranged for a transverse movement on the base 10 so that the wheel 50 may be fed toward or from the periphery of the roll 45 being ground so that the roll 5 may be ground to a predetermined size. The wheel feeding mechanism may comprise a half nut 60 depending from the under surface of the wheel slide 52 and arranged to mate with a rotatable feed screw 61 which is journaled in bearings 10 (not shown) in the base 10. The front end of the feed screw 61 carries a spiral gear 62 which meshes with a spiral gear 63 which is mounted on the lower end of a rotatable shaft 64. Shaft 64 is supported in a bearing 65 which is fixed to the base 10. The upper end of the shaft 64 carries a manually operable feed wheel 66 which is arranged so that rotation thereof will cause the feed screw to be rotated in either direction, depending on the direction of rotation of the hand wheel 66, so as to cause the half nut 60 to transmit a transverse feeding movement to the wheel slide 52 and the grinding wheel 50 to move the wheel either toward or from the work piece being ground.

25 The longitudinally reciprocable tables 32 and 37 are reciprocated preferably in synchronism with each other along their respective bases 11 and 12. These tables may be reciprocated by independent table reciprocating mechanisms, or in the preferred construction, one of the tables may be positively reciprocated and the other table operatively connected to follow the positively reciprocated table.

In the preferred construction, the table 32 is 35 connected to the table 37 by means of a link 70 which is pivotally connected to the table 32 by a stud 71 and is pivotally connected at its other end to the table 37 by a stud 72. The table 37 is positively reciprocated by means of a table 40 traverse mechanism to be hereinafter described, and due to the connecting link 70, the table 32 is reciprocated by the power transmitted by the table 37.

In the construction illustrated, a table traverse 45 or reciprocating mechanism has been illustrated, of the type shown in the prior patent to Norton No. 762,838 dated June 14, 1904, to which reference may be had for details of disclosure. As 50 illustrated in the drawings, the table 37 is provided with a depending rack bar 75 by which the table 37 may be traversed either by manual or power traverse mechanism, such as that shown in the above-mentioned prior patent. A gear 76 meshes with the rack bar 75 and is mounted on a rotatable shaft 77 which may be rotated manually by means of a gear 78 mounted on the outer 55 end of the shaft 77. The gear 78 meshes with a gear 79 which is rotatably supported on a stud 80. The stud 80 is supported by a bracket 81 mounted on the base 10. A manually operable table traverse wheel 82 is mounted on a hub of the gear 79 and connected thereto, by means of which the table 37 may be traversed longitudinally 60 on the base 10 through the gear 79, the gear 78, the shaft 77, and the gear 76 meshing with the rack bar 75.

The table 11 may be reciprocated longitudinally by a power operated mechanism, as shown in the prior patent above referred to. This mechanism 70 may comprise a rotatable power driven shaft 85 which is driven by a multiple speed drive contained within a casing 86, details of which have not been shown in the present case, since they are not considered part of the present invention. For details of this mechanism, reference

may be had to the above-mentioned prior patent. The rotatable shaft 85 drives a clutch member 86 which is arranged to engage either the clutch member 87 or the clutch member 88 which are formed integral with bevel gears 89 and 90 respectively. The bevel gears 89 and 90 mesh with a large bevel gear 91 mounted on the front end of a rotatable shaft 92. The large bevel gear 91 is rotated in either direction, depending upon the engagement of the clutch member 86 with either 10 the clutch member 87 or 88.

The clutch member 86 may be shifted automatically by means of a reversing lever 95 which is actuated by reversing dogs 96 and 97 which are adjustably supported in a T-slot 98 on the 15 front of the work table 37. The reverse lever 95 actuates a load and fire mechanism 99 to control the movement of the clutch member 86 to control the direction of reciprocatory movement of the table 37. The shaft 92 carries a gear 100 which meshes with a gear 101 mounted on a shaft 102. The shaft 102 also carries a gear 103 which meshes with a gear 104 mounted on the shaft 77.

In order that the power reciprocation of the 25 table 37 may be disconnected, a clutch member 108 is interposed between the gear 101 and the gear 103. When the clutch 108 is in the position illustrated in Fig. 4, the power reciprocation of the table is disconnected and the table 37 may 30 be traversed manually by rotation of the hand traverse wheel 82. A yoked member 109 engages the clutch member 108 and is supported for longitudinal movement by a shaft 110 which is actuated by a pivotally mounted lever 111 on 35 the front of the machine base. When the lever 111 is rocked toward the machine base, the shaft 110 is moved toward the left, as viewed in Fig. 4 to move the clutch member 108 in the same direction to engage it with a clutch member 112 40 which is formed integral with the gear 103. When the clutch member 108 is moved into engagement with the clutch member 112, the power rotation of the gear 91 is transmitted through the gear 100, the gear 101, the gear 103, the gear 104, 45 the gear 76, to the rack 75, to reciprocate the table 37 longitudinally relative to the base 10. For further details of disclosure as to the manual or power traverse of the table 37, reference may be had to the disclosure in the above-mentioned 50 prior patent to Norton.

As the table 37 is reciprocated either manually or by power, the table 32, due to the connecting link 70, will follow and be reciprocated through an identical stroke, thus moving in synchronism 55 with the table 37 so as to carry the work support 40 through the desired reciprocatory stroke.

In order to produce a predetermined crown on the periphery of the roll 45 being ground, the sub-bases 11 and 12 are adjusted to the desired 60 predetermined position by means of the screws 17 and 18 and 23 and 24, so that either a straight cylindrical surface may be produced or a concave crown, as desired. If the sub-bases 11 and 12 are adjusted so that the table ways 30, 31 and 65 35, 36 are in alignment with each other, then when the tables 32 and 37 are reciprocated, the roll being ground will travel in a straight line path and the grinding wheel 50 will grind a true cylinder on the periphery of the roll 45. If the 70 sub-bases 11 and 12 are adjusted into the positions illustrated in Fig. 2, namely so that the outer ends of the tables are moved toward the rear of the machine to an identical extent, the roll supporting table 40 instead of being moved 75

in a straight line path, will be carried through an arcuate path so as to generate a concave crown on the periphery of the roll 45. If desired to produce a convex crown on the periphery of the roll, the sub-bases 11 and 12 are adjusted so that their outer ends are moved toward the front of the machine, thus carrying the work supporting table 40 in an arcuate path so as to generate a convex crown or form on the periphery of the roll 45 as the tables 32 and 37 are reciprocated longitudinally to reciprocate the roll 45 relative to the grinding wheel 50.

The operation of this roll grinding machine will be readily apparent from the foregoing disclosure. The roll 45 to be ground is rotatably supported on the headstock center 48 and footstock center 49, and the sub-bases 11 and 12 are angularly adjusted by means of the adjusting screws 17, 18, 23 and 24, so that the index fingers 19 and 25 are moved to an identical position on the graduated scales 20 and 26 so as to produce the desired form on the periphery of the roll 45. As above explained, if the index fingers 19 and 25 are adjusted to the zero reading on the scale, that is the center graduation, the roll will be ground to a true cylinder. If the sub-bases are adjusted into the position illustrated in Fig. 2, with the index fingers 19 and 25 to the rear of the zero or center reading, then a concave crown will be produced on the roll being ground. If the index fingers 19 and 25 are adjusted forward of the zero or central reading on the scales 20 and 26, then a convex crown will be ground on the roll 45 as the table 40 is reciprocated by the longitudinally movable tables 32 and 37.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:—

1. A roll grinding machine having a rotatable grinding wheel and a rotatable work support which are movable longitudinally relative to each other, means to cause said wheel and work support to move transversely relative to each other, and means to move one of said elements in an arcuate path to grind a predetermined crown on the periphery of the work piece including a table to rotatably support one of said elements, a pair of spaced angularly arranged longitudinally movable tables, pivotal connections between said longitudinally movable tables and the ends of said first table, means to synchronously reciprocate said tables to cause a relative reciprocation between the wheel and work support, and adjustable supports for each of said longitudinally movable tables.

2. A roll grinding machine having a rotatable grinding wheel and a rotatable work support which are movable longitudinally relative to each other, means to cause said wheel and work support to move transversely relative to each other, and means to move one of said elements in an arcuate path to grind a predetermined crown on the periphery of the work piece including a table to rotatably support one of said elements, a pair of spaced angularly arranged longitudinally movable tables, pivotal connections between said lon-

gitudinally movable tables and the ends of said first table, means to synchronously reciprocate said tables to cause a relative reciprocation between the wheel and work support, adjustable supports for each of said longitudinally movable tables, and means to adjust the position of said supports to vary the arcuate path and thereby vary the extent of crown on the work piece. 5

3. A roll grinding machine having a rotatable grinding wheel and a rotatable work support 10 which are movable longitudinally and transversely relative to each other, means to cause said wheel and work support to move transversely relative to each other, means to move said wheel and work support longitudinally relative to each other, and means to move one of said elements in an arcuate path during said longitudinal movement to grind a predetermined crown on the periphery of the work piece including a table to rotatably support one of said elements, a pair of 20 spaced longitudinally reciprocable tables, pivotal connections between said longitudinally movable tables and the opposite ends of said first table, a sub-base interposed between each of said tables and the machine base, each sub-base having slide- 25 ways to support one of said tables, means to automatically reciprocate one of said tables, and connections between said positively reciprocated table and the other table to cause a relative reciprocation between the wheel and work support- 30 ing table to grind a predetermined curved or crowned face on the surface of the work.

4. A roll grinding machine having a rotatable grinding wheel and a rotatable work support which are movable longitudinally relative to each 35 other, means to cause said wheel and work support to move transversely relative to each other, and means to move one of said elements in an arcuate path to grind a predetermined crown on the periphery of the work piece including a table 40 to rotatably support one of said elements, a pair of spaced longitudinally movable tables, a sub-base interposed between each of said tables and the base, each sub-base having slideways to support one of said tables, pivotal connections be- 45 tween said longitudinally movable tables and the opposite ends of said first table, and means to synchronously reciprocate said tables to cause a relative reciprocation between the wheel and the work support to grind a predetermined curved or 50 crowned face on the surface of the work piece.

5. A roll grinding machine comprising a base, a transversely movable wheel slide thereon, a rotatable grinding wheel carried by said slide, means to feed said slide transversely relative to the base to cause the grinding wheel to approach or recede from the work piece, a rotatable work support including a table, a pair of spaced longitudinally movable tables each of which is pivotally connected to opposite ends of said work 60 supporting table, a pair of spaced swivel sub-bases on said base arranged to support said longitudinally movable tables, means to simultaneously traverse said tables longitudinally relative to said swivel bases to reciprocate the rotatable 65 work support relative to the grinding wheel, and means to adjustably swivel said sub-bases relative to the base of the machine so that the ways thereon are at an angle to each other so that when the tables are reciprocated, the work sup- 70 porting table and rotatable work support are moved through an arcuate path to grind a predetermined convex or concave crown on the roll being ground.

6. A roll grinding machine comprising a base, 75

a rotatable grinding wheel, a transversely movable wheel slide to support said wheel, means to move said slide transversely relative to the base to cause the grinding wheel to approach or recede from the work piece, a work supporting table, a rotatable work support on said table, a pair of spaced longitudinally reciprocable tables, pivotal connections between said tables and the ends of said work supporting table, a pair of spaced adjustably swivelled sub-bases supporting said tables and interposed between said longitudinally movable tables and the base, said sub-bases having ways to slidably support the spaced reciprocable tables, a reciprocating mechanism which is operatively connected to reciprocate one of said longitudinally movable tables relative to its supporting sub-base, connections between said spaced longitudinally movable tables so that the second longitudinally movable table follows as the other table is positively reciprocated, and means to angularly adjust the sub-bases relative to the machine base so that the table ways are in alignment with each other or at an angle to each other to grind either a true cylindrical surface or a convex or concave crowned surface on the roll being ground.

7. A roll grinding machine comprising a base, a transversely movable grinding wheel slide thereon, a rotatable grinding wheel carried by said slide, means to feed said slide transversely relative to the base to cause the grinding wheel to approach or recede from the work piece, a rotatable work support including a table, a pair of spaced longitudinally movable tables each of which is pivotally connected to the opposite end of said work supporting table, a pair of spaced swivel sub-bases on said machine base arranged to support said longitudinally movable tables, means to simultaneously traverse said tables longitudinally relative to said sub-bases to reciprocate the rotatable work support relative to the grinding wheel, and means including a graduated scale associated with each of said sub-bases to adjust the angular position of the sub-base relative to the machine base so that the ways thereon are at an angle to each other so that when the tables are reciprocated, the work supporting table and rotatable work support are moved through an arcuate path to grind a predetermined convex or concave crown on the roll being ground.

ALBERT G. BELDEN.
HERBERT J. GRIFFING.
